UNITED STATES PATENT OFFICE.

ROBERT BROWN, OF BIRMINGHAM, ENGLAND.

ELECTRIC TRACTION.

SPECIFICATION forming part of Letters Patent No. 666,258, dated January 22, 1901.

Application filed August 21, 1900. Serial No. 27,599. (No model.)

To all whom it may concern:

Be it known that I, ROBERT BROWN, a subject of the Queen of Great Britain and Ireland, and a resident of Broad Street Metal Works, 5 15 Broad street, in the city of Birmingham, England, have invented certain new and useful Improvements Relating to Electric Traction, (for which I have filed an application in Great Britain, No. 1,407, bearing date January 23, 1900,) of which the following is a specification.

This invention consists of improvements relating to electric traction, and especially to that system in which the current passes from 15 the main conductor or conduit beneath the road to the car-motor.

The object of my invention is to provide simple and more reliable means for effecting the automatic electrical connection and disconnection of the several contact-pieces with the motor as the car moves along the rails or track with a minimum interference with the street and at small cost.

On the accompanying sheets of explanatory drawings, (two in number,) to be hereinafter referred to, Figure 1 is a sectional side elevation representing portions of the underframe of an electric car and of the track on which it runs, having my invention applied thereto. 25 Fig. 2 represents a cross-section of the track. Fig. 3 is a similar view to Fig. 1, but with the car arranged to collect the current from studs disposed along the center of the track. Fig. 4 represents a cross-section of the track, showing one of the central collecting-studs. 30

The same reference-letters in the different views indicate the same parts.

In carrying my invention into effect I arrange at the required pitch or distances along 40 the conduit contact-pieces which each consist, preferably, of a pulley, as A, mounted upon a lever B. The said contact-pieces are normally out of contact with the main conductor, as hereinafter described, and with each 45 I employ a suitable switch and place the complete device in a box, as D, of larger capacity and section than the conduit E. The switch is preferably formed by providing the lever B with a central arm, as b, which can be 50 placed in contact with or withdrawn from a terminal c of the main conductor C in the manner hereinafter described.

Beneath each car, as F, I arrange a pair of arms or brackets, as G G', one at each end of the car, which project through the narrow slot 55 in the track and into the channel or conduit E beneath. To the inner extremities of such arms or projections I attach the respective ends of a wire rope or other flexible medium H, hanging between the arms G G' and arranged to pass over the contact-pieces, such as the aforesaid pulley A, as the car travels along the track. The said wire rope or other flexible medium H, hanging between the car projections, is of sufficient weight to depress 60 one end of the lever B, on which the pulley A is mounted, and so operate the switch (by pressing the central arm b into contact with the terminal c) as to electrically connect the contact-piece (formed by the said pulley A) 65 with the main conductor C. As the rope leaves the pulley A, mounted on the lever B, the latter is overbalanced or returned to its normal position by a weight or by a spring, as J, and the switch thus disconnects the 70 main conductor and the contact-piece. 75

The pulley or other contact-pieces are arranged or disposed at such a distance apart that before the disconnection of one switch a connection of the switch next in advance 80 shall have been effected by the suspended rope or flexible medium moving with the car.

If studs in the middle of the track are used, (such as the stud K at Figs. 3 and 4,) the current is collected from such studs by brushes 85 or a long strip or skate, as L, carried beneath the car and conveyed to the motor in any ordinary manner. The current passes direct from each switch to the adjacent stud when the switch is closed or put into circuit in the 90 manner hereinbefore described.

Where the lever and pulley in the channel are used to operate the switch by the weight upon it of the rope or flexible device carried by the car in the slot and the lever and pulley are electrified or put into circuit and used to collect from, as in the manner hereinbefore described with reference to Figs. 1 and 2, then the rope or flexible medium collects the current from the lever or pulley, and it is 95 passed from thence to the motors in the usual way.

I preferably make the shallow channel or conduit E from a combination, with one of

the ordinary track-rails, as M, of an outer rail or bar N, and thus the conduit is not deeper than the ordinary rail for the greater part of its length. The cast boxes D, of the necessary capacity, are arranged at the required intervals.

The enlarged box or chamber D gives facilities for electric insulation and attention through the roadway for repairs or renewals. 10 The conduit is thus made up of boxes of cast-iron or of cemented or concreted chambers connected with the main drainage to get rid of rainfall and connected from chamber to chamber by a small shallow slot or conduit E for the rope or flexible medium to pass through.

Having thus described my invention, what I claim as new, and desire to secure by Letters Patent, is—

20 1. In electric traction, the combination with a flexible medium H hanging loosely between a pair of arms G G' depending from the car, of a conduit E, box D, a three-armed lever B mounted within the said box, a pulley A rotatable upon one arm of the said lever, a spring J connected with the opposite arm, and a contact c fixed adjacent to the outer end of the central lever-arm b, the said contact being in constant electrical connection with the main conductor C, substantially as described. 25

tatable upon one arm of the said lever, a spring J connected with the opposite arm, and a contact c fixed adjacent to the outer end of the central lever-arm b, the said contact being in constant electrical connection with the main conductor C, substantially as described. 30

2. In electric traction, the combination with a flexible medium H hanging loosely between a pair of arms G G' depending from the car, of a conduit E, box D, a three-armed lever B mounted within the said box, a pulley A rotatable upon one arm of the said lever, a spring J connected with the opposite arm, a contact c fixed adjacent to the outer end of the central lever-arm b and in constant electrical connection with the main conductor C, collect- 35 ing-stud K, and skate L, substantially as described.

In witness whereof I have hereunto set my hand in presence of two witnesses.

ROBERT BROWN.
